UNITED STATES PATENT OFFICE.

LYNDE BRADLEY, OF MILWAUKEE, WISCONSIN.

AUTOMATIC RESISTANCE-CONTROLLER.

1,191,273.

Specification of Letters Patent. Patented July 18, 1916.

Application filed January 22, 1914. Serial No. 813,665.

To all whom it may concern:

Be it known that I, LYNDE BRADLEY, a citizen of the United States, residing at Milwaukee, county of Milwaukee, and State 5 of Wisconsin, have invented new and useful Improvements in Automatic Resistance-Controllers, of which the following is a specification.

My invention relates to improvements in 10 automatic resistance controllers of that type in which a compressible resistance medium is employed, such for example as the column of carbon disks shown and described in a former patent, numbered 1054902, dated 15 March 4, 1913, issued to L. and H. L. Bradley, for resistance devices.

The object of my invention is to provide 20 means for automatically varying the pressure upon a compressible resistance member in proportion to variations in conductivity due to temperature changes, whereby the resistance or conductivity of the medium may be kept substantially constant. I am thus 25 enabled to adjust the pressure upon my improved resistance column at the initial or starting temperature and no further changes in manual adjustment will be required to maintain a constant resistance notwithstanding the rise in temperature due to the 30 passage of the electric current through the resistance medium.

In the drawings—Figure 1 is a front elevation of a current controller embodying my invention, in which a pair of resistance 35 columns is employed. Fig. 2 is a side elevation with one of the columns removed, on line $x-x$ of Fig. 1, portions of the frame and clamping members being shown in cross section.

40 Like parts are identified by the same reference characters in both views.

The resistance columns are similar to those shown in my former patent above referred to. Each column comprises a series 45 of carbon disks 1 mounted in a tubular casing 2 against insulating head pieces 3. The column inclosing casings 2 are supported from a backing or plate 5 by a spider frame 6 and connecting bolts 7, said frame 6 being 50 provided with clamping members 8 and 9, which are adapted to embrace the tubular casings 2, to which they are secured by clamping bolts 10. The clamping members 8 and 9 are insulated from the casings 2 by 55 sleeves 11 of asbestos or other suitable material. Pressure is applied to the column

disks 1 by means of rods 12, which extend through the end caps 13 of the casings and bear upon end disks 14 which cap the ends of the columns. The rods 12 are actuated 60 by means of a pressure applying bolt 15 threaded in a traveling nut 16, the motion of which, when actuated by the bolt, is transmitted to the rods 12 through a set of pivot pins 17 and a frame 18 having outwardly 65 projecting arms 19 bearing against the insulated heads 20 on the outer extremities of said rods 12. The bolt 15 is provided with a head 22 and operating handles 23, the head being adapted to bear upon the backing 70 5 or upon a bearing plate 24 interposed between it and said backing. The other end portion of the bolt passes loosely through a central aperture 25 in the spider member 6 and is provided with an end nut 26. A spiral spring 27 is interposed between the nut 26 and the spider member 6.

When the bolt 15 is turned in a direction to apply pressure to the heads 20 of the rods 12, such pressure is transmitted through the 80 carbon disks to the outer or free ends of the casings 2. The casings 2 therefore pull outwardly upon the spider member 6, which is clamped to the casings by the members 8 and 9. This outward pull upon the spider 85 member draws it forcibly against the spiral spring 27, compressing the latter. The columns are thus placed under the resilient reactionary pressure of the spring 27, that is to say, each of the columns is pushed by 90 its rod 12 against a resilient cushion.

The casings 2 are formed of a material which expands under the influence of heat, thereby tending to relieve the pressure upon the disks 1, as the heat generated by 95 the current passing through the columns, increases the temperature of said casings. It has been found by experiment, however, that it is virtually impossible to secure accurate regulation of these variations in pressure by selection of an appropriate material or composition for the casings 2, since the carbon disks are comparatively inelastic and a very slight lengthening of the casing tubes 2 would be sufficient to relieve substantially all the pressure upon the disks, if said columns were compressed against a 100 fixed abutment. This would of course provide a positive temperature coefficient. But by interposing the cushion spring 27 between these casings and the fixed abutment 105 26 against which they press it is possible to 110

utilize the reactionary and expansive pressure of the spring to offset to some extent the expansion of the casing, whereby a very slight variation of pressure upon the carbon 5 column is secured. It will of course be understood that the nut 26 is locked upon the bolt 15 by any suitable means, such as the pin 30, said nut having been previously adjusted in its proper position upon said bolt. 10 In operation, the columns being without pressure, it is merely necessary to actuate the handles 23 to rotate bolt 15 in a direction to cause nut 16 to move outwardly on said bolt, said nut being prevented from 15 turning with the bolt by forked arms 31, which loosely engage the supporting bolts 7. The motion of the nut will then be transmitted, as above explained, through the arms 19, head 20, and compression rods 12 20 to the disks 1, thus compressing said disks against the outer or free ends of the tubes 2, said pressure being transmitted through the tubes and the spider 6 to the resilient cushion formed by the spring 27. The pivot 25 pins 17 and frame 18 permit an equalization of pressure upon the compressing rods 12 of the respective columns. The screw 15 will be turned until the desired pressure upon the columns is secured, whereupon the 30 resistance of the columns will be reduced in accordance with the pressure exerted, until the required conductivity is attained, as described in my said former patent. If no changes in conductivity are required, the 35 device may then be left without any further manual adjustment. An electrical current passing through the column or columns will have no substantial effect upon the conductivity thereof on account of the 40 temperature rise necessarily developed therein, for the reason above stated, that the casing tubes will expand and cause a slight diminution in pressure sufficient to compensate for the increased conductivity which 45 would result from the increase in pressure due to heat if the casing tubes 2 were not linearly expandible.

The specific construction illustrated, by 50 which the spring is located outside of and away from the columns is intended to remove the spring from the influence of heat developed in the columns from the current which traverses them. The apparatus is of course adapted to offset the effects of temperature variations due to either internal or 55 external causes, but external temperature variations will not ordinarily be such as to affect the durability or resiliency of the spring. I therefore prefer to separate the 60 spring cushion from the column or columns instead of inserting it between the disks and the end of the column, or between the disks and the compression rods 12. But aside 65 from the effects of heat upon the resilient cushion, its specific location in the line along

which the pressure is exerted, is not very material.

I claim—

1. An automatic resistance controller for compressible rheostats, comprising the 70 combination with a set of compressible resistance columns, and compressing means, of an abutment, a resilient cushion located between the columns and interposed between the abutment and the compressing 75 means, and a thermostatically operated member adapted by expansion, to relieve the pressure upon said cushion.

2. The combination with a current controlling compressible resistance member, of 80 a thermostatically expansible casing therefor, means for compressing said member within the casing, and a resiliently cushioned abutment supporting said casing and to which the pressure is transmitted 85 through said casing.

3. In an electric current controller, the combination of a plurality of compressible resistance mediums, containers for said mediums, means for producing pressure on 90 said mediums, means for equalizing the pressure on said mediums, and supporting means for said containers, said containers, at the ends opposite to those upon which the thrust of the resistance medium is received, being attached to but insulated from, said supporting means near the end at which the pressure is applied.

4. In an electric current controller, the combination of a compressible resistance 100 medium, a container for said medium, means for producing pressure on said medium, and a support attached to, but insulated from said container at the end opposite to that upon which the thrust of the compressed resistance medium is received and 105 near the point where the pressure is applied.

5. The combination with a compressible resistance medium for controlling electric 110 circuits, a spring adapted to maintain said medium under pressure, a member expansive under the influence of heat, means for heating said member, means for utilizing the expansion of said member to vary the 115 tension of said spring in such proportion to its variation in conductivity due to heat, as to maintain a substantially constant conductivity of said resistance medium.

6. In an electric current controller, the 120 combination of a compressible resistance medium and container for said medium, said container expansive under the influence of heat and exposed to the heat of said medium, means for compressing said medium, a support for said container attached to and insulated from said container at the 125 end opposite to that upon which the thrust of the compressible resistance medium is received, a spring for maintaining pressure 130

on said medium and means for utilizing expansion of said container to vary the tension of said spring in such proportion to the variation in conductivity of the resistance medium as to maintain a substantially constant resistance.

7. The combination of a set of compressible resistance columns, a casing inclosing each column, clamping members embracing said columns, a rod extending through one of the clamping members, a cushion spring interposed between one end of the rod and said clamping member, a nut screw threaded on said rod, a pressure bar pivotally connected with said nut, and insulated posts in-

terposed between the pressure bar and said columns.

8. The combination of a set of compressible resistance columns, a thermostatically expansible casing for each column, a support for said casings, a screw having resilient swivel connection with the support, and a nut on said screw in pressure relation to the columns.

In testimony whereof I affix my signature in the presence of two witnesses.

LYNDE BRADLEY.
